UNITED STATES PATENT OFFICE.

HARLOWE HARDINGE, OF YORK, PENNSYLVANIA, ASSIGNOR TO HARDINGE COMPANY, INCORPORATED, OF YORK, PENNSYLVANIA, A CORPORATION OF NEW YORK.

DUST CLASSIFIER.

Application filed August 23, 1925. Serial No. 53,174.

This invention relates to classifiers such as are used in the classification and the extraction of coarse material and fine material from a body of material laden air or other buoyant 5 or elastic fluid capable of carrying particles in suspension.

Heretofore, classifiers of the air current and cone-shaped variety and other varieties of two compartment classifiers have been 10 used, but these have been of such inflexible design that a very narrow range of adjustment was possible and the result was that the classifier designed for the classification of a particular material was at its best efficiency 15 when a certain grade of powder of that material was being produced. It is among my purposes of invention to be able to use an apparatus of the cone-shaped variety or of any other variety having two compartments 20 for classifying different substances and different grades of the same substance efficiently, and to obtain this result by making the various parts relatively adjustable so as to create the best condition for the different 25 classifications.

Another object resides in providing a general assembly comprising a dust classifier susceptible to being adjusted for the separation of dust of various degrees of fineness, together 30 with a disintegrating mill which serves the purpose of pulverizing coarse material, a cyclone or dust collector for the purpose of collecting the product of separation in the form of dust, and connections therebetween including a blower to maintain a dust carrying fluid in circulation throughout the entire assembly and dampers and valves to aid in the proper distribution and necessary regulation of the pressure of the moving mass of 35 dust carrying fluid throughout the assembly.

Another object of the invention resides in the provision of a two-cone separator capable of relative adjustment for varying the lifting capacity of the air passing between the 40 cones.

Another object resides in the design of deflecting blades such as will cause various degrees of fineness of material to be separated out from the current of material laden air 45 passing thereover, depending on the particular area of the surfaces of the blades that are rendered effective by being exposed to the passing current of material laden air.

Another object is the provision of a valve- 50 less return passage to reconvey oversize ma-

terial into the path of strong currents of air without having the valve closed or allowing the counterflow of air therethrough.

Other objects involving novel constructions and combinations of parts will appear 60 in the specification and in the claims thereof setting forth a preferred embodiment of my invention which will be fully understood from the detailed description and drawings, in which,

Fig. 1 is a general view showing the operative relation of the classifier with a rotating mill.

Fig. 2 is a sectional view of the classifier.

Fig. 3 is a perspective view of the top of the 70 classifier looking from the inside and clearly showing a design of the deflector blades according to one modification.

Fig. 4 is a diagrammatic illustration of another modification of the arrangement of the 75 deflector blades.

Fig. 5 is an elevation of a general assembly illustrating a third modification of a manner of exposing various amounts of surface of the deflector blades to passing currents of 80 air.

I have chosen to describe my invention according to a preferred working combination, and this is illustrated in Fig. 1, wherein the classifier is directly connected to the discharge 85 end of a rotating mill 1 from which a stream of material laden air or other fluid is continually being drawn. The mill is suitably mounted for rotation on bearings which are not shown for the purpose of simplicity in 90 illustration. Coarse material is fed to it by means of hopper 2 and owing to its rotary motion and design the finely pulverized material seeks the surface and approaches the discharge end. Air is blown into the rotat-

ing mill from conduit 3, through a section of pipe 4, and it leaves the mill by following a path along the outside of pipe 4 and through a barrel 5 into a conduit leading to the classifier. In the mill, the pulverized material is continually being agitated by the rotation of the mill and the moving air becomes laden with material and is then drawn through the barrel where the coarse particles drop out. Some of the pulverized material may overflow at the discharge end of the mill and fall into the barrel 5. The rotation of the barrel causes the material that has dropped into it to be raised in a manner similar to the process recurring in the mill, and this material is 105 110

dropped into a break between conduit 3 and pipe 4 whereby the current of air flowing through conduit 3 and pipe 4 returns it to the mill. The stream of air going to the 5 classifier will pass through the screen of falling dust and automatically collect therefrom its carrying capacity of fine material. It is not necessary that my improved classifier be used with this type of mill, but satisfactory 10 result have been attained through the use of the combination described.

In order to control the flow of air through the classifier a fan 6 is provided which is driven by a motor 7. This fan draws from 15 the top of the classifier through pipe connection 8 and discharges a steady stream of air, laden with an impalpable powder, into a collector 9 which may be of any desirable design, such as that of the well known cyclone 20 type.

Referring more particularly to the classifier, 10 is the exterior cone which forms the envelope encasing the means by the use and adjustment of which powdered products of 25 varied fineness are obtainable. This cone may be made rigid enough to support itself or be supported by any suitable structure, and it has near its apex a large opening through which a rapidly moving stream of 30 material-laden air enters. This opening is connected to the barrel of the mill by a conduit 11 and all the material that enters the classifier comes through this conduit. The lower end of the cone forms a pocket 12 which 35 opens into the air feed duct 3 of the mill, and all of the over-sized material which is separated out from the air current passing through the classifier is exhausted through the pocket and into the duct. Just below the 40 pocket exhaust opening there is an adjustable baffle 13 for constricting the area of the duct at this point which causes an increase in the velocity of flow of air in the duct and a consequent increased exhausting effect from the 45 interior of the cone.

Centrally located within the outer cone is suspended an inner cone 14 entirely open at its top and having a large opening at its apex. It is not of the same slope as the outer 50 cone and its upper end 15 is cylindrical.

The opening in the bottom of the inner cone is partially closed except for an annular opening created by a conically shaped member 16 which is adjustable relatively to 55 the inner cone for varying the size of the opening.

This member may be shaped substantially as shown in Fig. 2 and it is loosely mounted on a rod 17 passing through its axis. The 60 upper end of the rod is fastened to a bar 18 which extends to the inner walls of the cone 14 and is fastened thereto by suitable means such as rivets. The lower end of rod 17 is maintained in a definite vertical position by 65 a brace 19. A satisfactory manner of posi-

tioning the member 16 is by sliding it up or down on rod 17 and locking it in the desired position by means of a large cotter pin or the like passing through holes in the neck 20 and rod 17. A door 21 may be provided for 70 ready access thereto.

The conical member is wider at its central girth than the bottom of the inner cone and this causes the velocity to be less at the opening than that in the area opposite the central 75 girth of the conical member with the result that the tendency of the air is to follow along the area between the two cones and not enter within the inner cone.

In the embodiment illustrated in Fig. 2 80 there is fastened to the inner side of the inner cone and near its top a tubular member 22 with its upper edge on or about a level with the upper edge of the inner cone. Any suitable manner of fastening may be provided, 85 as, for example, straps 23, which I have chosen to show in this embodiment.

The top of the outer cone consists of a truncated cone 24 having a flange 25 at its base creating a detachable connection with the outer cone 10, and having a neck or pipe 26 connecting it with the exhaust pipe 8. Within this neck or pipe there is a sleeve 27 which extends into the inner chamber and has supported therefrom a closure member 28 95 consisting of two cones arranged base to base and supported by the suspension rods 29 fastened to sleeve 27. The size of the exhaust opening is dependent upon the position of the closure member and this position is adjustable by lock nuts 30 on each rod. The closure opening also eliminates eddy currents at this point and deflects the air in the proper directions.

Fastened to top 24 are a plurality of deflector blades 31 of twisted configuration and equidistant from one another (Fig. 3). Their lower ends are maintained in spaced relation by a ring 32. The lower part of each deflector 31 extends downwardly between the concentric walls 15 and 22, and the annular area covered by a horizontal cross-section of all of the deflector blades at any place does not exceed the annular area between the vertical walls 15 and 22. This arrangement allows for an adjustment of the surface of the deflector blades that is to be exposed for purposes that will appear hereinafter.

The lower edge of each blade is radially disposed and the top edges are preferably much longer, and, in this embodiment, make an angle of a little less than 90° with the radial edge. The angularity and length of the top edges is dependent upon the maximum whirling motion desired and is subject to alteration depending upon the capacity of the apparatus used and the fineness of material to be produced. The surface between the upper and lower edges of each deflector is 120 125 130

curved in such a manner as to give a whirling motion to the passing air, the intensity of which depends on the amount of vertical deflector surface which is exposed to the current of air. If the inner cone is in a low position, the passing air will be but slightly whirled, but if the top of the inner cone and member 22 are in a raised position, the whirling motion will be greater, for all of the air must pass through the part of the deflectors which gives it the greatest change in direction. Hence, the effective surface of the deflector is determined by the area that is covered and comprises the area exposed to the passing currents of air.

The inner cone and its attached appurtenances is suspended by rods 33. Each is secured at its lower end to bar 18 and the upper end is threaded and passed through a boss 34. A nut carrying a handwheel 35 forms a means by which the cone is raised or lowered.

The length of sleeve 27 has some effect on the selectivity of the classifier and the open end may be positioned in the approximate position illustrated in Fig. 2 or in a raised or lowered position depending upon the material that is being produced.

In Fig. 4 I have illustrated a modified form of my invention, in which the deflector blades 30 are contiguous with and preferably fastened directly to the outer cone along their outer edges and to the cone top along their upper edges, and the cylindrical wall 15 of the inner cone is within the circle described by the inner side edges of the blades. The deflector blades are of a twisted configuration similar to the construction described hereinbefore, except that the horizontal projection of the inner edges describes a circle of slightly greater diameter than the outer diameter of cylindrical wall 15. No member such as collar 22 is necessary in this construction, for the vertical exposure of the blades is controlled entirely by the position of the inner cone which may be raised and lowered for the purpose.

The material of which the cones and ducts are made comprises preferably sheet metal of sufficient weight to obtain rigidity and strength in construction, and is lapped, riveted, and preferably soldered or welded so as to be certain of an air-tight condition. It is obvious that many other ways of construction are adaptable without departing from the spirit of the invention.

During the process of classification of various grades of material, a current of air, or of any other suitable fluid medium that will carry by its motion pulverized material, is drawn into the inlet 11 of the outer cone directly from a mill where the raw material is pulverized. When it enters from the inlet it flows into a cross-sectional area larger than the inlet duct and its velocity is correspondingly decreased. This allows the coarser pieces to drop and collect in the

pocket near the apex of the outer cone from whence they are drawn into the air feed duct for the mill and returned for further crushing. The finer particles are carried along by the current of air between the two cone surfaces and through the deflectors. The current of air will then be whirled by the deflectors an amount depending on the distance of the top of the inner cone from the roof of the outer cone, Figs. 1 and 2, and the coarse particles remaining therein will be thrown to the inner sides of the inner cone and will slide down to the annular opening at the bottom thereof. The finer particles will be taken along with the air and exhausted through a pipe leading to the collector.

The raising of the inner cone enlarges the mean effective area between the two cones with a consequent drop in velocity, thereby creating a reduction in lifting capacity of the moving air. In the raised position the smaller of the coarser particles will of themselves drop back to be reconveyed to the pulverizer. In this position of the inner cone, the lower part of the deflectors will be eliminated from functioning and the material-laden air must pass through the deflectors at their greatest pitch. This will create a greater centrifugal action so that only very fine particles will be carried along with the air and out to the collector.

It is obvious that when the inner cone is in its lowest position a coarser product will result, for the velocity of the air rising between the two cones is greater, and larger particles will be carried to the top. Also the deflectors are not covered to any extent and the air will not be given as great a whirling motion as when the cone is in a raised position, with the result that a coarser product will be retained in the air current.

In Fig. 5 I have illustrated a general assembly differing from that illustrated in Fig. 1 and including still another modification of adjustable structure for causing a whirling motion of passing currents of air. In this modification, the deflector blades are of the same style and disposed similarly to those illustrated in Fig. 4. However, a collar 36 is introduced between the inner edges of the deflector blades and the cylindrical wall 15 of the inner cone. This collar is supported on hangers 37, the upper ends of which are threaded and pass through bosses 38. A nut carrying hand wheel 39 bears upon each boss, and affords means for positioning the collar. This arrangement has the advantage that the effective area of the deflector blades is determined by the position of the collar independent of any relative movement between the two cones. In this modification the inner cone could be fixed in relation to the outer cone and all adjustment for different degrees of separation of dusts accomplished by vary-

ing the effective area of the deflector blades by manipulation of the collar.

The delivery conduit 40 of the classifier leads directly into the product collector 41 in which the product is removed from the current of air and the air withdrawn from the collector through conduit 42 by fan 43. The exhaust of the fan is connected to the mill by conduit 3, and a vertically disposed pipe 44 exhausts whatever extra air that is drawn into the system as a result of infiltration. This pipe is open at its upper end, and a valve 45 may be used to control the amount of air exhausted. Under certain conditions it is preferable to drive air into the classifier directly instead of forcing all of the air through the mill, and this is accomplished by the interpositioning of a by-pass conduit 46 between conduit 3 and conduit 11. Valve 47 is adjustable to regulate the amount of air that will be delivered directly to the classifier.

My invention is capable of a wide variation and relationship of parts without departing from the nature and principle thereof, and I do not restrict myself unessentially in the foregoing or other particulars, but contemplate such alterations and modifications within the scope of the appended claims as may be found to be advisable.

What I claim is:

1. In an apparatus of the class described, the combination of an outer cone and an inner cone relatively movable and so related in respect to one another as to allow a current of material-laden fluid to flow between their respective surfaces, said inner cone being open at the top and having disposed thereat in definite relation with the outer cone a set of deflectors of twisted configuration for controlling the whirling effect of the material-laden fluid passing therethrough, and said outer cone having an opening at the bottom for the entrance of material-laden fluid and an exit at the top for the expulsion of the fine product suspended in a current of fluid after the coarser material has been extracted therefrom by the whirling action of the material-laden fluid passing through the deflectors.

2. In an apparatus of the class described, the combination of an outer cone and an inner cone relatively movable and so related in respect to one another as to allow a current of material-laden fluid to flow between their respective surfaces, said inner cone being open at the top for permitting the fluid to enter the inner space of said cone and being closed at the bottom by a conical member except for an annular opening through which passes oversize material discarded by the fluid current which is directed towards an exhaust pipe having an entrance through said outer cone.

3. In an apparatus of the class described, the combination of an outer casing and an inner casing relatively movable and so related in respect to one another as to allow a current of material-laden fluid to flow between their respective surfaces, said inner casing being open at the top for permitting the fluid to enter the inner space of said casing and open at the bottom for permitting the discharge of oversize material, and means for restricting the opening at the bottom so proportioned as to deflect a rising current of material-laden fluid away from said opening.

4. In an apparatus of the class described, the combination of an outer cone and an inner cone relatively movable and so related in respect to one another as to allow a current of material-laden fluid to flow between their respective surfaces, said inner cone being open at the top for permitting the fluid to enter the inner space of said cone and being closed at the bottom by a conical member except for an annular opening through which may pass oversize material discarded by the fluid current, said outer cone having an entrance near its lower end for admitting said current of material-laden fluid, an exhaust at its upper end for conducting away the fine product suspended in fluid, and an opening at its lower portion for excluding the extracted coarser materials.

5. In an apparatus of the class described, in combination, an outer casing and a relatively movable inner casing, deflectors secured at the top of said outer casing and arranged concentric to the rim of said inner casing and having their lower edges substantially radially disposed and their upper edges at an angle with their lower edges, and means for varying the relation of said inner casing in respect to said outer casing and deflectors in order to expose a variable amount of surface of said deflectors to the passage of fluid.

6. In an apparatus of the class described, in combination, an outer casing and a relatively movable inner casing, deflectors disposed intermediate the upper extremities of the two casings so as to affect all fluid passing therebetween, and means for cutting out a portion of said deflectors from functional relation with the fluid currents.

7. In an apparatus of the class described, in combination, an outer casing and an inner casing, deflectors disposed at the upper extremities of the two casings so as to affect the fluid passing therebetween, and means for varying the exposure of said deflectors to said passing fluid.

8. In an apparatus of the class described, in combination, an outer casing and a relatively movable inner casing, deflectors having a twisted configuration varying in pitch from one edge to another, and means in cooperative

relation with said inner casing for rendering ineffective variable amounts of surface of said deflectors.

9. In an apparatus for classifying materials, comprising in combination an outer casing and an inner casing describing two spaces, deflectors disposed therebetween to affect the passage of fluid from one space to another, and means for varying the effective 10 surface of said deflectors to change the course of the passing currents of fluid.

10. In an apparatus for classifying materials, comprising in combination an outer casing and an inner casing describing two 15 spaces, deflectors disposed therebetween to affect the passage of fluid from one space to another, means for covering a portion of said deflectors, and adjusting means for moving said inner casing and for varying the 20 amount of covered surfaces of said deflectors.

11. In an apparatus for classifying materials, comprising in combination an outer casing and an inner casing describing two spaces, deflectors disposed therebetween to 25 affect the passage of fluid from one space to another, means for covering a portion of said deflectors, and means for independently moving said inner casing.

12. In an apparatus for classifying materials, comprising in combination, an outer casing and an inner casing describing two spaces, the outer space being adapted to be 30 varied in cross sectional area throughout its length, deflectors interposed in communication between the two spaces, and means for simultaneously varying the amount of cross 35 sectional area and the effective surface of the deflectors.

13. In an apparatus for classifying material, an outer casing and an inner casing having an opening near its lower portion, a valve member normally extending within said opening and having a portion thereof of greater

girth than the opening for preventing fluid currents from entering the inner casing 45 through said opening and permitting the discharge of solid material from the inner casing, and means for adjusting the relative position of the valve member.

14. In an apparatus of the class described, 50 comprising, in combination, an outer casing having inlet and outlet openings, an inner casing having an open side for permitting material-laden fluid to enter from the outer side of said inner casing, deflectors disposed 55 in the path of material-laden fluid flowing along the outer side of said inner casing, and means for varying the amount of area of said deflectors which is effective to deflect the material-laden fluid flowing from between 60 the inner and outer casings and towards said open side of said inner casing.

15. In an apparatus of the class described, comprising in combination, a container for separating materials, said container having 65 inlet and outlet openings, a casing within said container, deflector blades intermediate said inlet and outlet openings, and means for varying the area of said deflector blades effective upon the fluid advancing toward said 70 outlet opening.

16. In an apparatus of the class described, comprising in combination, a container for separating materials, said container having inlet and outlet openings, a casing having 75 an opening therein, and a valve member for said opening, said valve member being conoidal and having two apices, one of which extends into said opening, and the other of which extends away from said casing whereby fluid currents are prevented from entering said inner casing through said opening. 80

In testimony whereof I hereto affix my signature.

HARLOWE HARDINGE.
